UNITED STATES PATENT OFFICE.

HARLEY C. RALSTON, OF CLEVELAND, OHIO, ASSIGNOR TO THE AMERICAN STEEL AND WIRE COMPANY OF NEW JERSEY, A CORPORATION OF NEW JERSEY.

WIRE-DRAWING APPARATUS.

Application filed December 8, 1922. Serial No. 605,608.

To all whom it may concern:

Be it known that I, HARLEY C. RALSTON, a citizen of the United States, and resident of Cleveland, in the county of Cuyahoga and

State of Ohio, have invented certain new and useful Improvements in Wire-Drawing Apparatus, of which the following is a specification.

This invention relates to wire drawing blocks and while not limited thereto relates particularly to drawing blocks used in drawing wire by the continuous method, and has for its object the provision of a block having compensating mechanism thereon for taking up variations in the length or tension of the wire between successive drafts.

Another object is to provide a novel wire drawing block having the construction, design and combination of parts hereinafter described and illustrated in the accompanying drawings.

In the drawings, Figure 1 is a typical side elevation of a wire frame or drawing bench having a drawing block constructed in accordance with this invention mounted thereon.

Figure 2 is a sectional elevation through one of the drawing blocks of Figure 1.

Figure 3 is a similar view taken on the line III—III of Figure 2.

Referring more particularly to the drawings the numeral 2 designates a wire drawing bench or frame as a whole, on which are mounted a series of drawing blocks A, B, C and D, and a series of die blocks E, F, G and H. The drawing blocks A, B and C are of novel compensating design, while the block D is of the usual standard finishing or take-up design. The die blocks E, F, G and H are of standard and well-known design.

Each of the drawing blocks is keyed or otherwise secured on vertical shafts or spindles 3 which extend downwardly through the bench 2 and carry bevel gears 4 adjacent their lower ends which mesh with bevel gears 5 mounted on a main drive shaft 6, which is journaled in suitable bearings 7 on the bench 2. The gears 4 are normally in driving engagement with the shafts or spindles 3 through clutches 8, but when it is desirable or necessary to interrupt the operation of any one of the drawing blocks the gears 4 may be rendered

inoperative by disengaging the respective clutch 8 from the gear 4 by depressing the foot pedal lever 9 which operates the clutch 8 through lever 10, which is pivoted intermediate its ends on a bracket 11 and has a sliding connection 12 with the upper half 13 of the clutch.

The clutches 8 may be of any desired design, although a standard friction clutch is preferred and is shown in the drawing.

The drawing blocks A, B and C are of novel compensating design and comprise a drum portion 14 which is keyed to the shafts or spindles 3 and provided with an upper lip or flange 15 to prevent the wire slipping off over the upper edge.

The drum 14 is provided with a centrally arranged aperture in its upper wall for the reception of a nut 16, through which a vertical shaft 17 passes into the interior of the drum.

A friction disc 18 is mounted on the inside of the bottom wall of the drum and secured thereto by dowel pins 19. A housing 20 is loosely mounted on the squared lower end 21 of the shaft 17, and a second friction disc 22 is secured to the housing 20 by dowel pins 23 and bears against the disc 18.

A spider member 24 is splined on the shaft 17 above the housing 20, and guide rods 25 are mounted in the spider 24 and housing 20 to guide and form mountings for compression springs 26 which are tensioned to normally force the housing 20 and disc 22 against the disc 18. The tension of the springs 26 is adapted to be adjusted by adjusting the nut 16 on the shaft 17 so as to vary the position of the spider 24, thereby compressing the springs 26 or allowing them to extend, depending on whether the nut is moved downwardly or upwardly on the shaft.

From the above it will be readily seen that the friction discs 18 and 22 form a yieldable drive for the shaft 17, which will have a tendency to always rotate the shaft 17 with the drum 14.

A compensator arm 27, having a sleeve portion 28 mounted on and keyed or otherwise secured to the shaft 17 is provided with guide sheaves 29 and 30 adapted to receive and guide the wire from the drum portion 14. The guide sheave 29 is journaled on the outer end of an arm extension 31 which is angularly offset with relation to the verti-

cal axis of the arm 27 and is transversely inclined so that its horizontal axis is inclined downwardly with respect to the horizontal axis of the drum, in a direction away from the drum, whereby the sheave 29 is inclined downwardly away from the drum and projects beyond the same.

The sheave 30 is journaled in bearings 33 in the arm 27 above the sheave 29 and on a line with the vertical axis of the arm, and is of such size that its grooved periphery extends over and on a line with the central axis of the shaft 17.

A bearing pin 34 is disposed vertically in a sleeve 35 on the upper end of the arm 27, and a bracket 36 is journaled thereon together with a ball thrust bearing 37 so as to provide for a free swiveling movement of the bracket. The pin 34 is provided with a central aperture 38 which aligns with a second aperture 39 in the bracket 36 to form a wire conduit or guideway. The bracket 36 is provided with outwardly extending arms 40 between which is mounted a third guide sheave 41, which has its periphery in alignment with the center line of the apertures 38 and 39.

Suitable retaining pins 42 are mounted adjacent or close to the periphery of each of the sheaves 29, 30 and 41, respectively, to prevent the wire leaving the sheaves when slack.

The wire is adapted to be trained from the drum 14 around the sheave 29 in a clockwise direction, then over the inside of sheave 30, through the apertures 38 and 39, and over the sheave 41.

A fourth sheave 44 is journaled on each of the die blocks F, G and H and the wire from the preceding draw block is adapted to be trained down under the sheave 44 and thence passed through the die.

The operation of this apparatus, assuming that the wire is being pulled through the die block E by the draw block A is as follows:--The wire is drawn through the die block E, several turns are taken around the drum portion of draw block A, and it is then passed around the sheave 29, under sheave 30, through apertures 38 and 39 in the pin 34 and bracket 36, respectively, over sheave 41, and then down under sheave 44 on the die block F and through the die block F to the next draw block B. The wire is then successively passed onto the draw block B, through die block G, onto draw block C and through the die block H in the same manner as described above, and from the die block H the wire is wrapped upon the standard take-up block D.

The wire in the process of drawing is reduced in area and consequently increased in length as it is drawn through each successive die block. Therefore each successive draw block is driven at a successively

higher speed so that their peripheral speeds will be in proper ratio to the increased length of wire. However, due to causes beyond control, such as the wear of the dies, and variation in the stock being drawn, the amount of reduction by the dies and consequent lengthening of the wire may vary so as to be greater or less, thus causing uneven tension on the wire, which either causes the wire to break or to become loose on the preceding drum.

The present invention with its compensating arms 27 provides for eliminating this variation in tension. The wire in passing from the drum portion 14 of the block onto the sheave 29 of the compensating arm pulls on the sheave in a counter-clockwise direction, while the drum portion is rotating and tending to rotate the compensating arm in a clockwise direction. The pull of the wire on the sheave 29, due to the fact that the sheave is mounted on the arm extensions 31 serves to pull or rotate the arm 27 in a counter-clockwise direction. However, due to the friction drive between the drum 14 and arm 27, if the dies are each reducing the wire the theoretically correct amount, the pull of the wire on the sheave 29 and the friction drive will counterbalance each other, and the compensating arms will remain stationary or in neutral position. It will be obvious, however, that in practice the reduction in the dies will vary and consequently the tension between the dies and blocks will vary. If the tension between a die and the preceding die block becomes greater than normal the compensating arm on the draw block will be rotated in a counter-clockwise direction relative to the drum portion 14, thus unwrapping sufficient wire from the drum to relieve the tension, and if the tension becomes slack or less than normal the compensating arm will rotate with the drum portion 14 a sufficient amount to wrap wire upon the drum and again establish the normal tension.

The sheaves 41, due to the bracket 36 being swiveled on the pin 34 always remain in a plane parallel with the sheaves 44 and the die blocks so as to deliver the wire to these parts.

If for any reason the amount of wire on the drum portion of any of the draw blocks becomes less than desired the succeeding block may be temporarily slowed down by rendering the clutch 8 for that block inoperative by applying pressure to the foot treadle 9, thus decreasing the relative demand for wire and allowing the first named block to build up its supply.

In a similar manner, if the amount of wire on any draw block increases to its full working capacity, it may be slowed down momentarily by operating its clutch 8 and thus increase the relative demand for

wire by the succeeding draw block, thus reducing the amount of the first named block.

While I have shown and described only one specific embodiment of my invention it will be understood that I do not wish to be limited thereto, since various modifications and substitutions or equivalents may be made without departing from the scope of my invention as defined in the appended 10 claims.

I claim:

1. A wire drawing block for use in continuously drawing wire comprising a drum portion means for positively rotating said drum portion, a vertically disposed compensating arm mounted axially on said drum and rotatable relative thereto, a pair of guide sheaves mounted on said arm and movable therewith, the lower one of said 15 sheaves being offset with relation to the vertical axis of said arm and having its axis slightly inclined from the vertical so as to take wire tangentially from the drum portion, a third sheave mounted on the upper 20 end of said arm and rotatable relative thereto, friction drive mechanism between said drum portion and said arm tending to normally cause said arm to rotate with said drum portion, the wire being adapted to pass from said drum portion over said lowermost and angularly positioned sheave, then over said second and third sheaves to the next preceding die, the tension of the 25 wire on said lowermost sheave overcoming the power of said friction drive member when the tension on the wire exceeds a predetermined maximum.
2. In apparatus for continuously drawing wire, a series of dies, a series of wire drawing blocks alternately arranged with respect to said dies, a compensating arm mounted for rotary movement on each of said blocks, said compensating arm comprising a central shaft mounted axially on the block and 30 having a pair of guide sheaves mounted thereon and movable therewith, one of said 35

sheaves being offset with relation to vertical axis of said arm and having its axis slightly inclined from the vertical so as to take wire tangentially from the block, a 50 third guide sheave mounted on said arm and movable independent of said arm, and means tending to normally rotate said arm with said block, the wire being adapted to be taken from said blocks and passed over said 55 guide sheaves in passing to the succeeding die, and tension of the wire on said offset sheave being adapted to rotate said arm relative to the block when the wire tension exceeds a predetermined amount. 60

3. A wire drawing block for use in continuously drawing wire, comprising a drum portion, means for positively rotating said drum portion, a vertically disposed compensating arm mounted axially on said 65 drum and rotatable relative thereto, a plurality of guide sheaves mounted on said arm in spaced vertical relation, the lower one of said sheaves being fixed to said arm and offset with relation to the vertical axis 70 of said arm and having its axis slightly inclined from the vertical so as to take wire tangentially from the drum portion, the upper one of said sheaves being mounted on the upper end of said arm and rotatable relative thereto, friction drive mechanism between said drum portion and said arm, tending to normally cause said arm to rotate with said drum portion, the wire being adapted to pass from said drum portion over 75 said lowermost and angularly positioned guide sheave on said compensating arm and over said upper guide sheave when leaving said arm, the tension of the wire on said lowermost sheave overcoming the power of 80 said friction drive member when the tension on the wire exceeds a predetermined maximum.

In testimony whereof I have hereunto set my hand.

HARLEY C. RALSTON.
